UNITED STATES PATENT OFFICE.

BELDEN D. JONES, OF CHICAGO, ILLINOIS.

CAR-DOOR.

1,015,387.

Specification of Letters Patent. Patented Jan. 23, 1912.

Application filed June 15, 1911. Serial No. 633,316.

To all whom it may concern:

Be it known that I, BELDEN D. JONES, a citizen of the United States, residing at Chicago, in the county of Cook and State of Illinois, have invented certain new and useful Improvements in Car-Doors, of which the following is a specification.

This invention relates to improvements in car doors, and has among its salient objects to provide a construction which effectively forms a close, waterproof fit with the car body to prevent any water or moisture from entering the car, and at the same time allows the door to be freely opened and closed; to provide a construction which avoids any unprotected joints between the car-door opening and the car-door itself and at the same time allows for warping and other distortion of the door structure when subjected to weather conditions; to provide in a device of the above character means for protecting the joints exposed to the weather which can be applied to any of the well known freight cars now in use; and in general to provide improved details of construction in a device of the above character.

The invention consists in the matters hereinafter described, and more particularly pointed out in the appended claims.

In the drawings.—Figure 1 is a fragmentary side elevation of a freight car equipped with my invention, and showing the car door in closed position; Fig. 2 is a vertical sectional view of the same, taken on the line 2—2 of Fig. 1; Fig. 3 is a similar horizontal sectional view; Fig. 4 is a view similar to Fig. 3, but showing a somewhat modified construction.

Difficulty is experienced in practice in obtaining a weather proof door structure which at the same time will not bind after it has been subjected for some time to weather conditions. Numerous devices have heretofore been patented intended to overcome the above objection, but they have usually either been too complicated, or, if weatherproof, would not open and close readily after the door had been in use for an appreciable length of time. The present invention is intended to overcome the above difficulty, and at the same time is characterized by its simplicity and economy of construction.

Referring now more particularly to the drawings, I designate as a whole the car body, provided with a sliding door 2. To

the upper end of the door are secured brackets 3, 3, in which are journaled track wheels 4 riding in a channel-way 5 secured to the upper end of the car body. Across the upper end of the door 2 is secured a Z-bar 6, the upper end of which projects into a longitudinally extending recess 7 formed by the car body and the trackway 5. The lower edge of the door 2 is provided with a somewhat similar Z-bar 8, the depending flange 9 of which projects into confining brackets 10 secured to the lower end of the car body. The manner of supporting the door, however, forms no part of the present invention.

Referring now particularly to the manner of forming the weather-proof fit, between the door and car opening, at either end of the latter is secured a vertically extending angle-iron 12 by suitable screws 13, these angle-irons, in effect, forming the door posts. The outer flange 14 of the post 12 is spaced away from the side of the car body to form a vertically extending channel 15.

When the door is in closed position, as shown in Fig. 3, it abuts at one end against the door stop 16, and the inner face of the door lies against the flange 14 of the angle-irons 12. Any moisture which may leak between the door stop 16 and the edge of the door will pass out through the channel 15 instead of entering the car body. The same is true in a general way of the other end of the door. However, as a substantial feature of the invention and in order to more fully protect the joint at the opposite end of the door against the entrance of moisture or water, I provide a weather-guard 17 which is preferably formed of an angle iron, one flange 18 of which is secured by bolts 19 to the outer edge of the door, and the other flange 17' of which projects inwardly beyond the inner edge of the door. It is to be noted particularly that the flange 17' of the weather-guard is spaced away from the adjacent edge of the door so as to form a vertical passage or channel 20 open at either end. It has been found in practice that this construction absolutely prevents any moisture from entering the car at this end of the door, and, at the same time, does not interfere with the opening or closing of the door when the latter becomes warped by the weather. In order to more effectively brace the flange 17' against jamming, I provide a space block 21 about mid-height of the door. The upper and lower ends of the

flange 17' are protected against jamming or being otherwise bent inwardly against the door by means of extensions 22 and 23 of the upper and lower Z-bars 6 and 8, referred to in Fig. 2. In other words, these Z-bars project outwardly beyond the rear edge of the door a slight distance so as to brace the flange 17'.

In Fig. 5 is shown a somewhat modified construction, in which 12' designates the door post, 16 the door stops, and 2 the door. At that end of the door remote from the stop 16, there is provided a similar weather-guard 18' secured to the door in exactly the same manner as the weather-guard 18 heretofore described. The door is also provided at its upper and lower edges with the Z-bars 6 and 8 and extensions 22 and 23 heretofore described. The inward portion of the guard is braced by means of a rivet 18" instead of the space block 20 shown in Fig. 3.

In the construction shown in Fig. 4 the vertical channel between the weather guard 18' and adjacent post 12' effectively prevents any moisture from leaking into the car body.

The construction and operation of the invention are apparent from the foregoing description.

30 The invention is not limited to the details of construction shown except as set forth in the appended claims.

I claim as my invention:

1. The combination with a car body having a car door opening, of a door mounted to move across said opening, a door post at either end of said opening, a door stop at one end thereof, and a weather guard comprising an angle iron secured to the door at its end remote from the stop one flange of said angle iron extending across the vertical edge of the door but spaced away from the latter to form a vertical channel.

2. The combination with a car body, having a car door opening, of a door mounted to move across said opening, a door post at either end of said opening, a door stop at one end thereof and a weather guard com-

prising an angle iron one flange of which is secured to the outer face of the door at the 50 end of the latter remote from the stop and the other flange of which extends across the vertical edge of the door and projects beyond the inner face of the latter, said latter flange being spaced away from the vertical 55 edge of the door to form a vertical channel.

3. The combination with a car body, having a car door opening, of a door mounted to move across said opening, a door post at either end of the latter, a door stop at one 60 end thereof and a vertically extending weather guard secured to the end of the door remote from the stop and provided with a flange portion extending across the vertical edge of the door but spaced away 65 from the latter and projecting inwardly beyond the inner face of the door.

4. The combination with a car body, having a car door opening, of a door mounted to move across said opening and an angle 70 iron extending vertically along one edge of the door, one flange of which is secured to the outer face of the door and the other flange extending across said vertical edge but spaced away from the same.

5. The combination with a car body, having a car door opening, of a door mounted to move across said opening, a door post at either end of said opening, a door stop at one end thereof and a weather guard comprising a vertically extending angle iron, one flange of which is secured to the outer face of the door at the end of the latter remote from the stop and the other flange of which extends across the vertical edge of 85 the door and projects some distance beyond the inner face of the latter, said latter flange being spaced away from the said vertical edge to form a weathering channel and means for bracing said latter flange against 90 jamming.

BELDEN D. JONES.
